(57) **CLAIM**

The ornamental design for a massage implement, as shown and described.

DESCRIPTION

FIG. 1 is a left side elevational view of the massage implement showing my new design, the right side being a mirror image thereof;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side elevational view of the massage implement of FIG. 1 shown in an alternate condition; and, FIG. 7 is a left side elevational view of the massage implement of FIG. 1 with the roller portion shown in a rotated condition.

The broken lines are for illustrative purposes only and form no part of the claimed design.
